UNITED STATES PATENT OFFICE.

EDWARD J. FOWLER, OF REDWOOD CITY, CALIFORNIA, ASSIGNEE TO PACIFIC FOUNDRY COMPANY, OF SAN FRANCISCO, CALIFORNIA; A CORPORATION OF CALIFORNIA.

ROASTING-FURNACE.

1,079,405.

Specification of Letters Patent.

Patented Nov. 25, 1913.

Application filed May 3, 1913. Serial No. 765,252.

To all whom it may concern:

Be it known that I, EDWARD J. FOWLER, a citizen of the United States, residing at Redwood City, in the county of San Mateo and State of California, have invented certain new and useful Improvements in Roasting-Furnaces, of which the following is a specification.

My invention relates to the class of roasting-furnaces employing a vertical series of hearths successively communicating at rim and center alternately, and having rabble-arms rotating above each hearth and driven by a central shaft; and it especially relates to those furnaces of this class in which air is employed to serve the double function of cooling the rabble-arms and furnishing oxygen to the furnace.

My invention has for its object the better accomplishment of both these functions and of stiffening and strengthening the rabble-arms, said objects being attained by an improved circulation and disposition of the air; and to this end my invention consists in a furnace of this type provided with a novel and improved rabble-arm as the instrumentality by which the result is reached, all as I shall now fully describe by reference to the accompanying drawings in which—

Figure 1 is a vertical section of my furnace. Fig. 2 is a horizontal section of one of the rabble-arms. Fig. 3 is an inner end elevation of the arm of Fig. 2. Fig. 4 is a horizontal section of a rabble-arm embodying my invention but slightly modified with respect to the number of its air delivery openings.

1 is the furnace shell.

2 are the hearths in vertical series communicating successively at the center openings 3 and the rim openings 4, alternately, in usual manner.

5 is the central shaft driven in suitable manner, as, for example, by the main shaft 6 below, through the gears 7.

8 is a clutch on the main shaft.

9 is the smoke flue above the furnace, which receives the smoke through the outlets 10.

11 is the receiver for the material discharged from the furnace.

12 are the rabble-arms, and 13 are the rabbles carried by the arms. The arms 12 are secured to the rotating shaft in any suitable manner. For illustration I here

show a flange 14 on the inner end of the arm, which is belted to a flange 15 on the shaft.

The shaft 5 is hollow throughout its length. Its foot is closed, but its upper end 60 which extends through the furnace top has rotary connection with an elbow 5' which elbow is to have communication with a source of air under pressure, not shown. Each rabble-arm 12 is also hollow throughout its 65 length. Its outer end is closed, but its inner end is in free communication with the cavity or bore of the central shaft 5. Each rabble-arm is fitted or formed with an inner partition wall 16 which lies in the vertical median longitudinal plane of the arm and traverses the cavity thereof from top to bottom. This partition 16 at its inner end springs from the side wall of the arm and thence extends toward but terminates short of the 75 outer closed end of the arm, so that the cavity of the arm is divided into two longitudinally directed channels 17 and 18, one of which 17 at its inner end communicates freely with the cavity of the central shaft 5 and at its outer end communicates with the outer end of the other channel 18.

In the side wall of the arm proximate to its connection with the central shaft is made an opening 19, which leads from the inner 85 end of the arm channel 18 directly into the furnace. This opening 19 need not be a single opening as is shown in Figs. 1 and 2, for as I show in Fig. 4, it may be plural, but its position proximate to the inner end 80 of the arm is essential in order to provide for the necessary maximum air circulation throughout said arm.

It will now be seen that the air circulating throughout the length of the arm from 90 its inner end to its outer end and back again to its inner end has a maximum course length, conducive to its function of cooling the arm; and it will be seen further that said air, heated to its best efficiency by 100 reason of its extensive course, is discharged into the furnace with such advantage as will follow the supply of heated air thereto. Furthermore, this air by keeping the partition wall 16 cooler than the outside walls of 105 the arm, will permit said inner wall 16 to best serve its additional and important function of a stiffener or strengthener for the arm, to prevent it from sagging. To elaborate this, I may state that in practice 110

this partition wall 16 is preferably of cast iron, and as it will be kept by the air at approximately 700 to 800 degrees Fahr. and as at such temperature cast iron is at its maximum strength, it will best strengthen and stiffen the arm and keep it from sagging.

It is to be noted that the cavity or bore of the shaft 5 is continuous. This results in 10 furnishing practically equally cool air to all the rabble-arms, instead of increasingly heated air to successive arms, as would be the case if the cavity of the shaft were so obstructed as to cause the same air to circulate from the shaft through one set or tier 15 of arms and back again to the shaft, then through a succeeding set of arms and back to the shaft and so on.

I claim:—

2. In a roasting furnace of the described class, the combination of the hearths; a single central rotatable hollow shaft having a continuous longitudinal cavity adapted to receive and convey air; and the hollow rabble-

arms connected at their inner ends with said 25 shaft and having their outer ends closed, each of said arms having within it a longitudinal partition wall terminating short of the closed outer end of the arm and dividing its cavity into two longitudinally directed 30 channels, one of which communicates at its inner end with the cavity of the hollow central shaft, and at its outer end with the other channel, said latter channel at its inner end being closed to the cavity of said 35 shaft, and each of said arms having in its wall an opening proximate to the connection of the arm with the central shaft, said opening leading from the inner end of said other channel directly into the furnace. 40

In testimony whereof I have signed my name to this specification in the presence of two subscribing witnesses.

EDWARD J. FOWLER.
